WORK FABRICATING MACHINE

Ernie L. Launder, Montebello, Allen W. Leudon, Downey, and Max Frederick, Jr., Whittier, Calif., assignors, by mesne assignments, to H. & L. Tooth Company, Montebello, Calif., a corporation of California

Application February 24, 1953, Serial No. 338,292

28 Claims. (Cl. 219—124)

This invention has to do with a work fabricating machine, it being a general object of the invention to provide a machine which is operable to handle an electric arc and welding material in connection with work or parts to be assembled, so that the parts are accurately, securely and dependably held as the arc is maintained and the welding material fed, and while relative movement is generated between the work and the arc where the material is fed, to the end that the work is welded at various parts, for instance, continuously about a particular portion, or as circumstances may require.

This application is copending with our applications: Serial No. 631,573, filed December 31, 1956, entitled Welding Head; Serial No. 674,754, filed July 29, 1957, entitled Mounting for a Welding Head in a Work Fabricating Machine; and, Serial No. 718,316, filed February 28, 1958, entitled Table and Clamp for Supporting and Holding Work in a Fabricating Machine.

The machine which is the object of the present invention can be used to advantage in the fabricating of various parts by welding. However, it is particularly practical and can be used to great advantage in the fabricating of digger teeth, or the like, and it will therefore be described in this connection. When reference is made to the work acted upon as being a digger tooth or as being digger teeth, it is to be understood that this particular reference is made merely to facilitate an understanding of the invention and furthermore, when a particular tooth construction is referred to, it is to be understood that such detail is set forth merely to facilitate an understanding of the invention.

It is a general object of this invention to provide a machine adapted to readily receive work parts that are to be assembled, and which carries an electrode at or from which a rod of welding material is fed, and which serves to move the work parts and the electrode relatively and in a predetermined manner, to the end that the parts are welded one to the other and, as the cycle of the machine is repeated, successive like work parts are likewise welded.

Another object of this invention is to provide a machine of the general character referred to, which is such that the work parts are readily applicable to the machine and are effectively held and electrically connected preliminary to the machine going into action to apply welding thereto.

Another object of this invention is to provide a machine of the general character referred to, whereby a line of welding is applicable to the work parts to establish a continuous loop or ring of welding, the form of which corresponds to the work parts and may, for example, be rectangular in plan configuration when the work parts require that form of weld.

Another object of the present invention is to provide a machine of the general character referred to, including numerous improved elements which, considered individually, incorporate features of the present invention.

Another object of this invention is to provide a machine of the general character referred to, characterized by a

simple combination, arrangement and relationship of parts.

A further object of the invention is to provide a machine of the general character referred to, characterized by construction and arrangement of parts which make for simple, inexpensive manufacture, as well as practical, dependable, rapid operation.

The various objects and features of the invention will be fully understood from the following detailed description of typical preferred forms and applications of the invention, throughout which description reference is made to the accompanying drawings, in which:

Fig. 1 is a front elevation of the machine provided by the present invention, being a view showing the front end of the machine and showing work in the machine and the parts positioned or related ready for the machine to start a cycle of operation. Fig. 2 is a side elevation of the machine, being a view taken as indicated by line 2—2 on Fig. 1. Fig. 3 is a view illustrating a part of the means provided for supplying flux, showing a portion of the structure in section to illustrate the details thereof. Fig. 15 is an enlarged detailed plan sectional view of a portion of the structure, being a view taken as indicated by line 15—15 on Fig. 1. Fig. 16 is an enlarged view of a portion of the structure shown in Fig. 15 with the parts in a position different from that shown in Fig. 15. Fig. 17 is a view similar to Fig. 16, with the parts positioned different from that in Figs. 15 and 16. Fig. 18 is a detailed vertical sectional view of the structure shown in Fig. 15, being a view taken as indicated by line 18—18 on Fig. 15. Fig. 19 is an enlarged detailed sectional view of a portion of the structure shown in Fig. 18, being a view taken as indicated by line 19—19 on Fig. 18. Fig. 20 is an enlarged detailed sectional view taken as indicated by line 20—20 on Fig. 18. Fig. 21 is an enlarged view of a portion of the structure shown in Fig. 1. Fig. 22 is an enlarged view taken as indicated by line 22—22 on Fig. 21. Fig. 23 is an enlarged transverse sectional view taken as indicated by line 23—23 on Fig. 22. Fig. 24 is an enlarged detailed transverse sectional view taken as indicated by line 24—24 on Fig. 22. Fig. 25 is an enlarged sectional view of a portion of the structure shown in Fig. 6 at the left hand end thereof. Fig. 26 is an enlarged detailed sectional view taken at work located in the machine and showing

the general relationship of parts occurring in the machine at the work operated on thereby. Fig. 27 is a sectional view of the structure shown in Fig. 26, being a view taken as indicated by line 27—27 on Fig. 26. Fig. 28 is a perspective view of parts shown in Figs. 26 and 27, indicating the position of the welding rod after the first longitudinal movement has occurred as between the work and the rod and after the rod has completed its first turning movement. Fig. 29 is a perspective view similar to Fig. 28 illustrating the operation of the machine advanced from that shown in Fig. 28 and yet uncompleted. Fig. 30 is a perspective view similar to Figs. 28 and 29 showing the clamp of the machine removed from the work and showing the relative positioning of the parts as the operation of the machine terminates, except that the welding rod is shown turned from the terminal or starting position ready to make the first line of weld at the right hand end of the work. Fig. 31 is a perspective view of the work as it is finished by the machine and the condition in which it is removed from the machine. Fig. 32 is a perspective view of the work as shown in Fig. 31, with the two units of work parted. Fig. 33 is a view illustrating a unit of work of slightly different form from that illustrated in the preceding figures and showing it as it is removed from the machine, being a figure corresponding to Fig. 31. Fig. 34 is a view of the work shown in Fig. 33, with the work units parted, being a view corresponding to Fig. 32. Fig. 35 is a view similar to Fig. 1 showing a form of construction somewhat different than the simple form shown in Fig. 1 and showing a construction characterized by a table having a slide operating transversely thereof. Fig. 36 is an enlarged detailed sectional view of the flux control valve shown in Fig. 35. Fig. 37 is an enlarged detailed sectional view taken as indicated by line 37—37 on Fig. 35. Fig. 38 is an enlarged longitudinal view of the structure shown in Fig. 35, being a view similar generally to Fig. 35 and showing in particular the table construction including a slide that operates transversely thereof. Fig. 39 is a fragmentary perspective view of the structure shown in Figs. 35 and 38, certain of the parts being broken away to show details of construction. Fig. 40 is a longitudinal sectional view of the portion of the structure, being a view taken substantially as indicated by line 40—40 on Fig. 38. Fig. 41 is a diagrammatic view illustrating the hydraulic system as provided by the present invention, and Figs. 42, 43, 44 and 45 are diagrammatic views illustrating the electrical control system as provided by the present invention.

As has been pointed out, the present invention provides a machine that can be used to advantage to assemble or fabricate various parts or work and, since it is particularly practical as applied to the fabrication of digger teeth, it is shown in a form designed for that purpose, and in the drawings, digger teeth of typical form are set forth. For example, in Figs. 31 and 32, there is illustrated a digger tooth cap construction characterized by a flat heavy blade 10 and a cup-like sheet metal body 11 which is applied to one side of the blade to establish a tapered or converging cup-shaped opening 13 adapted to receive a tooth shank. As a digger tooth cap of the type referred to is used, the blade is ordinarily uppermost and the body of the cap is at what may be referred to as the back side 14 of the blade. The cap construction as shown in the drawings involves the body 11 having sides 15 and an end 16 that engage the back side 14 of the blade, and the machine of the present invention is provided to apply welding Z to join the sides 15 and end 16 of the body 11 to the blade 10.

To facilitate rapid production it is preferred that the machine of the present invention be employed to handle two caps simultaneously, in which case the blades 10 of these two caps are arranged with their bottom sides 14 end to end, so that these blades are oppositely disposed. The bodies 11 of the two caps are facing upwardly and 75

arranged on the blades, and in the case illustrated, up to and including Fig. 33 of the drawings, the abutting ends 17 of the blades 10 are flat and the cap design is such that the bodies 11 have ends 18 which abut. With the cap parts just referred to arranged as shown in Fig. 31 of the drawings, a single, continuous line of welding Z may be applied in rectangular form to extend around the two related caps, effectively joining the bodies of the caps to the blades, and when the welding has been completed the two caps are parted by severing or breaking the welding that occurs where the caps adjoin.

In the form of cap illustrated in Figs. 33 and 34, the blades 10, instead of having flat ends 17 that abut as above described, have tangs 17a on their ends, which tangs abut or adjoin, making it desirable to provide disposable inserts 19 between the opposing ends 17 to receive or carry the welding Z, which inserts break out as indicated in Fig. 34 and can be disposed of without appreciable loss.

In the following description of the machine, it can be assumed that either of the cap constructions just described is being handled, since the action of the machine in either case is the same. In the first form of the invention illustrated, that is, in the form of the invention illustrated in Figs. 1 to 36 inclusive, there is illustrated a simple form of the invention characterized by manual application of an assembly of parts, as shown in either Figs. 31 or 33, immediately preceding each operation of the machine upon such an assembly, whereas in the other form of the invention, illustrated in Figs. 35 to 40, inclusive, there is illustrated a form of machine embodying the invention having the general characteristics of the machine first referred to, but differing therefrom in that it simultaneously handles two assemblies of parts, one in the course of being worked upon by the machine, while the other is being installed ready to be worked upon in the next operation of the machine.

The first or more simple machine, as set forth in detail in Figs. 1 to 34 inclusive, includes primarily a frame A characterized by a rigid horizontally disposed elongate base 20 carried by suitable supporting structure, standards 21 projecting upward from the frame and supporting a horizontal top beam or header 22 and having rails 23 on the header 22 extending longitudinally thereof.

A work carrier B is provided and is characterized by a horizontally disposed elongate table 24 which in the form of the invention under consideration, is a simple, flat, horizontally disposed, rigid plate.

A fixture C is provided on the table 24 of carrier B, and where the table is elongate and extends to the forward end portion of the machine, the fixture is preferably fixed on or located at the forward end portion of the table. The fixture as provided by the present invention is characterized by a rest 25 for the work, and a retainer 26 cooperating with the rest and preferably serving to hold not only the work, but also flux employed as the welding operation is carried out.

A mounting means D is provided supporting the table 24 of carrier B on or from the base 20 of frame A for free movement or reciprocation of the table lengthwise.

An operating means E is provided to reciprocate or operate the carrier B relative to the base of the frame, and an operating means F is provided to operate the retainer 26 of the fixture C.

A work retaining means G is provided and is adapted to engage and hold work on or in the fixture C and is characterized by a shiftable jaw 28. A mounting means H is provided for the retaining means G and preferably includes a vertically shiftable stem 29, an arm 30 projecting from the stem and carrying the jaw 28, a carriage 31 carrying the stem for vertical reciprocation, rails 32 on the table 24 extending longitudinally thereof, and rollers 33 on the carriage 31 and engaging and supported by the rails 32.

An operating means I is provided to operate the stem of

means H relative to the carriage of means H and is preferably a structure carried by the carriage of means H to shift therewith.

An operating means J is provided for operating the carrier B or the table 24 lengthwise thereof and a stop means K is provided to limit the travel of the table 24 relative to the base 20, while a stop means L is provided to limit or determine the travel or movement of the carriage 31 of means H relative to the table 24.

An electrode M is provided to carry a welding rod or wire 35 and a mounting means for the electrode M includes a vertically disposed spindle N, a carrier or carriage O supporting the spindle for rotation about a vertical axis, means P mounting the carriage on the rails 23 of frame A and a head Q carried by the spindle. The head Q has an arm 40 which is horizontally disposed and fixed to the spindle and it has a case 41 on which a rod supply means R is mounted and in which a rod feeding means S is carried and on which the electrode M is mounted.

An operating means T is provided for actuating the carrier or carriage O so that it is reciprocated horizontally above the forward end portion of table 24, a drive means U is provided for turning the spindle N, and a stop means T' is provided to limit the travel of the carriage O.

A flux supply means V is provided and serves to supply flux to the work as welding occurs. A welding circuit W is provided and when in action includes the work and the electrode M. A hydraulic system X is provided and is illustrated diagrammatically in Fig. 41 of the drawings, while an electrical control system Y is provided and is illustrated diagrammatically in Figs. 42 to 45 of the drawings.

The frame A of the machine may, in practice, be varied widely in form and construction and, considered generally, this element of the machine is a mounting or support for the various other parts, as will be apparent from a consideration of the drawings. The base 20 of frame A is an elongate horizontally disposed unit having a front end 45 occurring at the front end of the machine, while side parts 46 extend longitudinally of the base 20 and to the rear end 47 of the machine. In a typical and preferred construction, the base 20 is a rectangular unit made up of elongate members or beams, and in the particular case illustrated, there are longitudinal beams 48 extending between the front and rear members of the base intermediate the sides 46. The longitudinal beams 48 are spaced apart to accommodate elements of the structure, as clearly illustrated in Fig. 8 of the drawings.

The standards 21 of the frame are located at the forward end portion of the base 20, and are spaced apart transversely of the machine, as clearly illustrated in Fig. 1 of the drawings. The standards 21 are like tubular members that carry the header or beams 22 so that it extends horizontally across the machine above the forward end portion of the base 20 and the table 24 carried by the base.

The rails 23 are carried by the beam 22 through suitable brackets 50, and they extend longitudinally of the beam and are horizontally disposed, as clearly illustrated in the drawings.

The work carrier B is provided to support one or more units of work as by means of the fixture C, and in its preferred form it is a part of the machine which reciprocates lengthwise of the base, and has a part or parts at the forward end portion of the machine to support the fixture C to be, in effect, beneath the beam 22 of the frame A. In the form of the invention under consideration, the carrier B is formed essentially of a simple flat, horizontally disposed plate or table 24, which is arranged lengthwise of or parallel with the base 20 of the frame. The table is located at the top of the base, preferably immediately above the top of the base, as clearly illustrated in Fig. 6 of the drawings.

The fixture C as provided by the present invention is, in practice, varied, depending upon the particular work handled by the machine. Where tooth caps are being handled and where these units of work have elongate blades arranged end to end, the fixture C is preferably formed so that it has a rest 25 with a flat top 60 forming a seat to be engaged by the blades of the caps. In the case illustrated, a lip or ridge 61 is provided at the forward edge portion of the rest 25 and projects upwardly somewhat above the top 60 of the rest and forms a stop 62 adapted to be engaged by the forward edges of the blades being handled in the machine.

The retainer 26 of fixture C as provided by the invention is a unit cooperating with the rest 25 and, in the case illustrated, it is a U-shaped member, with a main portion 63 which is straight and which extends parallel with the ridge 61 and is adapted to be arranged adjacent the rear edges of the blades handled by the machine. In the particular case illustrated, the main portion 63 of the retainer is adapted to engage or bear against the rear edges of the blades and the retainer is adapted to be operated so that it is urged forward, to the end that the blades between the portion 23 and the ridge 61 are clamped or held tight between these parts. Forwardly projecting parts or fingers 64 are provided in the ends of the main portion 63 of retainer 26. The fingers 64 are adapted to overlie the terminal end portions of the blades 10 on the rest 25 and extend to or closely approach the ridge 61.

With the construction just described, when the blades are held or clamped by the retainer, the combined retainer 26 and ridge 61 form a structure surrounding and projecting up from the portions of the blades engaged by the bodies of the caps. In the preferred construction, the edges or inner corner portions of the ridge 61 and the parts 63 and 64 of the retainer facing and, in effect, enclosing the bodies of the caps located on the blades that are engaged on the rest, are bevelled, so that there is, in effect, an upwardly opening trough established around the bodies of the caps where these parts engage the blades that are supported by the rest.

In practice, the fixture C is preferably releasably mounted on the table 24 as by means of one or more fasteners 66 and, in carrying out the invention, the electric circuit incidental to the welding operation is completed through the fixture, preferably through the rest 25, and for this purpose a conductor handling the welding circuit can be connected to the rest 25 or to an element of the machine to which the rest is grounded, say, for instance, the table 24.

The mounting means D provided for supporting the work carrier from the base is best illustrated in Figs. 6, 7 and 8 of the drawings. The means D in the case illustrated includes rails 70 carried by the longitudinal beams 48 of frame A, so that they are horizontally disposed and extend longitudinally of the beams, that is, lengthwise of the base 20. The rails 70, being thus mounted, are located below the table 24, and the table 24 has brackets 71 depending from it and carrying rollers 72 that suitably engage the rails.

A guide means D' is preferably provided to supplement the action of the mounting means D, and it serves to accurately guide the movement of the table 24 relative to the base 20 of frame A. In the form of the invention illustrated, the means D' includes guide rollers 72a suitably mounted on the top of base 20 and engaging the longitudinal parallel side edges 70a of the table 24. This general construction is illustrated in Figs. 4 and 5 of the drawings.

The operating means E provided to operate carrier B relative to base 20 of frame A is provided to effect power operation of the carrier and is preferably a fluid pressure actuated means. In the form of the invention illustrated in the drawings, the means E includes a fluid pressure actuated cylinder and piston mechanism 73a, the

cylinder 74 of which is anchored to one of the longitudinal beams 48, while the rod 75 thereof projects forward and is joined to the carrier B by a suitable coupling 76.

The operating means F provided to operate or reciprocate the shiftable retainer 26 of fixture C is a power-operated unit or mechanism and is preferably a fluid pressure actuated mechanism. In the case illustrated, the means F involves a cylinder and piston mechanism 80, the cylinder 81 of which is fixed on the table 24 at the rear end portion thereof, while the rod 82 thereof projects forward and is joined by a coupling 83 to a stem 84 which projects forward over the table 24 and connects to and carries the retainer 26. The stem 84 extends through and is guided by suitable bearings 85 mounted on the top of the table 24.

The work retaining means G is adapted to hold and engage the work or work parts in the fixture C. In the case illustrated, the means G is provided to hold or clamp the cap bodies 11 and the blades 10 together and on the rest 25. In the form of the invention illustrated the means G includes a vertically shiftable jaw 28 carried by the terminal end of arm 30 and depending therefrom.

The particular jaw illustrated in the drawings has a horizontally disposed body 90, and teeth 91 depend from the body 90 to engage the uppermost sides of the caps 11 as clearly illustrated in Fig. 26 of the drawings. The jaw 28 has side plates 92 and 93 which depend from the body 90 and which are adapted to engage over the uppermost portions of the caps 11 to be in contact with the sides of the caps, as clearly illustrated in Fig. 27 of the drawings. In accordance with the present invention, the side plate 92 is fixed relative to the body 90, while the plate 93 is shiftable relative to the body, being pivotally connected thereto by means of pivotal connections 94. A spring 95 under compression normally yieldingly bears against plate 93 and urges it toward the plate 92, and, as a result of this construction, when the jaw is engaged with the bodies 11 as shown in Figs. 26 and 27, there is a tight contact or gripping engagement established between the jaw and the work. With the construction above described, the teeth 91 engage the inclined or pitched uppermost surfaces of bodies 11, and serve to effectively center or locate the bodies 11 in the desired manner, as will be apparent from a consideration of Fig. 26 of the drawings.

The mounting means H provided for carrying the means G is characterized by the vertically shiftable stem 29 that carries the horizontally disposed arm 30 which in turn carries the jaw 28 of means G. In the preferred construction, the vertically disposed jaw 28 projects upward from the carriage 31 of means H and the arm 30 is fixed on the upper end of the stem 29 and projects forward therefrom so that the jaw 28 carried by arm 30 is supported forward of the carriage 31.

The carriage 31 supporting the stem 29 supports the stem for free vertical movement, and, in the construction illustrated, the carriage is equipped with a plurality of rollers 97 which effectively engage and support the stem, as clearly illustrated throughout the drawings and particularly in Figs. 6, 5 and 9 thereof. The stem and rollers are formed and engaged so that the stem will reciprocate freely but will not turn.

The rails 32 of the mounting means H are, in the case illustrated, carried by the table 24 at the under sides thereof, and are spaced parallel rails that extend longitudinally of the table 24 so that they are parallel with the rails 70 which support the table. The rollers 33 of means H are mounted on the carriage 31 to suitably engage the rails 32, and, in the construction illustrated, there are rollers 33 engaging the upper and lower faces of the rails 32, and there are also rollers engaging the opposed edges 98 of the rails 32, to the end that the carriage 31 is accurately supported by the rails and rollers for move-

ment lengthwise of the table 24. The table 24 has an elongate slot-like opening 99 which passes the carriage 31 so that it projects upwardly from below the table to a point above the table, as clearly shown throughout the drawings.

The operating means I, provided to shift the stem 29 relative to carriage 31 is a power means carried by the carriage 31, and it is preferably a fluid pressure actuated mechanism characterized by a cylinder and piston mechanism having a cylinder 100 carried by the carriage 31 and depending therefrom, while a piston rod 101 from the piston of the mechanism projects upwardly and connects to the lower end of stem 29. The general arrangement and construction of the means I is clearly illustrated in Fig. 6 of the drawings. The means I, being carried by the carriage 31, is at all times engaged with the stem so that the stem can be operated regardless of the position of the carriage, and by locating the means I at the bottom of the carriage so that it depends from the carriage, it is in no way interferes with other parts of the structure.

The operating means J provided for operating the carriage 31 of means H is a power means, preferably a fluid pressure actuated means, and in the preferred form of the invention, it includes a cylinder and piston mechanism, the cylinder 105 of which is fixed to the table 24 at the lower side thereof rearward of carriage 31. The piston rod 106 of the cylinder and piston mechanism of means J projects forward from the piston located in cylinder 105 to project from the cylinder 105, and a suitable coupling 107 connects the forward end of the rod 106 to the carriage 31, as clearly illustrated in Figs. 6 and 8 of the drawings. Through the action of the means J, the carriage 31 of means H can be shifted to move the jaw 28 of means G between a retracted position rearward of fixture C, as shown in Fig. 6, and a working position overlying the fixture C, as shown in Fig. 25, and from the foregoing description it will be immediately apparent that the operating means I serves to shift the stem 29 vertically, so that the jaw 28 can be moved into and out of engagement with the work while in the forward or working position.

The stop means K provided by the present invention serves to limit the movement of the table 24 relative to the base 20, which movement or operation is effected by the means E as hereinabove described. In the case illustrated, the means K includes a forward stop member 110 carried by the base 20 of frame A and adapted to be engaged by and to stop the work carrier when the table thereof has reached the desired forward position. A stop member 111 is carried by the base 20 and is adapted to be engaged by and to stop the carrier B when the table 24 thereof is in the desired rearmost position.

In the construction illustrated, the stop member 110 is in the form of a screw threaded to the base 20 at the forward end portion thereof, and it is located to be engaged by a part on or rigid with the table 24. In the particular case illustrated, the stop screw 110 is positioned to be engaged by the forward end of one of the parts 71 depending from the table 24 to carry rollers 72.

The stop member 111 is preferably a screw threaded to the base 20 at the rear end portion thereof and is located to cooperate with a fixed part 112 on the table depending from the bottom thereof, as shown in Fig. 8 of the drawings. Through the construction just described, the stop screws 110 and 111 can be readily adjusted to set the movement of the table 24 so that the table is operated the desired distance and is stopped in the desired positions when operated by the means E.

The stop means L is preferably carried by the table 24 of carrier B and serves to stop forward movement of carriage 31 of means H in a predetermined position relative to the table or to the fixture C located thereon. In the case illustrated, the means L includes a stop member 115 carried by the table at the lower side thereof, forward

of the carriage 31 and in a position to be engaged by a forwardly facing part 116 of the carriage. In the construction illustrated, the stop member 115 is a screw threaded to a part 118 depending from the bottom of the table 24, and it extends longitudinally of the table, so that it is adjustable to vary the position of its end 119 which opposes the carriage 31 and serves to stop forward movement of the carriage. In practice, by adjusting the screw 115, the machine can be set so that the jaw 28 supported by the means H is stopped in a predetermined forward position when the means J operates to move the carriage 31 of means H to its extreme forward position.

The electrode M is provided to handle the welding wire or rod 35 and in turn is carried by the head Q, which in turn is carried by spindle N. In practice, the electrode M may vary widely in form and construction, depending upon the welding material being handled, the particular work to be acted upon, and various other factors.

The particular electrode M illustrated in the drawings has a base plate 120 provided with a channel 121 adapted to slidably pass the rod 35. The plate 120 is elongate in form, and a contact 122 is mounted on it and projects forward from it to carry a tip 123. The contact 122 is secured to the plate 120 by screw fasteners 124, one of which may be employed to hold the terminal end of a conductor 126 in the welding circuit.

The tip 123 establishes a channel 128 continuing from channel 121 in plate 120 to pass the rod 35. The tip 123 has a converging forward end portion 130, at which the channel 128 terminates, so that the welding rod 35 issues from the tip in the manner clearly illustrated in Fig. 22 of the drawings. In the construction illustrated, the tip 123 is made up of a pair of blocks 123' fixed to the contact 122 by fasteners 131. One block 123' has slots 133 passing the fasteners 131 so that it can be adjusted relative to the other block 123' and thus establish the channel 128 so that it has the desired relation to the rod 35.

In the preferred construction, liners or facings 135 of hard or wear-taking material are provided on the opposed parts of the blocks 123' so that there is not excessive wear of the tip incidental to the passing of the rod 35 therethrough.

Where the conductor 126 of the welding circuit terminates at contact 122 as above described, it is preferred to provide a direct electrical connection 136 between contact 122 and the tip, for instance, between contact 122 and block 123' of the tip, as clearly shown in Fig. 22 of the drawings.

In the preferred construction, the electrode M includes a means whereby the blocks 123' are normally yieldingly urged toward each other so that there is maintained an effective contact between the tips thereof and the rod 35. In the case illustrated, a leaf spring 139 is carried by the plate 120 of the electrode M and it engages the movable block 123' to normally yieldingly bear against it, as indicated by the arrow in Fig. 22. The fasteners 131 are set to allow for the desired movement or shifting of the one block 123' relative to the other, and under the action of spring 139, the blocks 123' are maintained in sliding pressure engagement with the rod 35.

The mounting means provided by the present invention to carry the electrode M serves to support the electrode so that the tip thereof delivers the welding rod 35 at a particular point or in a particular location relative to the table 24 of the carrier, and more specifically, relative to the fixture C, and it supports the electrode so that its tip faces downwardly and inwardly toward that point, and so that the electrode as a whole is rotatable about a vertical axis intersecting at that point and can be moved as desired through a complete circle, that is, through 360° as circumstances may require.

The spindle N of the electrode mounting is an elongate vertically disposed element supported by carriage O to depend therefrom, and in the preferred form of the invention, it is tubular, being provided with a central tubular passage 140, which passage extends continuously through the spindle from one end to the other and is employed for the handling of flux, as will be hereinafter described.

The carriage O that supports the spindle N is in turn carried by the rails 23 of the frame A by the means P. In the preferred construction, the carriage O is supported between the rails 23, and the means P includes rollers 141 mounted on opposite sides of the carriage O to engage the tops of the rails 23, while rollers 142 on the sides of the carriage engage the bottom sides of the rails. Since the rails 23 are horizontally disposed and are spaced apart and extending lengthwise of the beam 22 of frame A, the carriage O is supported as just described for reciprocatory movement horizontally above the forward portion of the table 24, in fact above the fixture C on table 24.

The spindle N is supported by carriage O so that it is vertically disposed and rotatable. In the construction illustrated, and which is best shown in Fig. 11 of the drawings, the spindle N is supported in or by the carriage O through suitable anti-friction bearings 145, there being suitable bearings in the main or body portion 146 of the carriage, and a lower bearing at the lower end of an extension 147 of the carriage, which extension depends a substantial distance below the body 146 of the carriage. In the preferred construction a suitable brake or drag member 145a is carried by the carriage O and engages the spindle to maintain a certain amount of friction on the spindle so that it does not turn unless deliberately operated.

The head Q is supported by spindle N, preferably at or by the lower end portion thereof, and it in turn carries the electrode M and preferably carries other elements of the construction, including the means R and S. In the particular construction under consideration, the head Q is characterized by a case 41 with an arm 40 fixed to and projecting horizontally from the case, preferably from the upper end thereof. The arm 40 has an opening 148 at its outer or terminal end passing the lower end portion of spindle N. The portion of spindle N passing through the opening 148 has flattened sides 149 and the opening 148 is correspondingly shaped, so that the arm is, in effect, keyed on or set relative to the spindle N against rotation relative to the spindle. A bracket portion 150 of the carriage extension 147 overlies the end portion of the arm 40 engaged in passing the spindle, and a retainer or nut 151 on the spindle is provided beneath the arm, as clearly illustrated in Fig. 11 of the drawings. Because of the manner in which the welding circuit is handled in or by the machine, the arm 40 of head Q is electrically insulated from the spindle as by suitable insulation 155 provided where the spindle and arm are related as shown in Fig. 11 of the drawings.

The case 41 of head Q is supported by the arm 40 so that it is laterally offset from the spindle N and it depends from the arm as clearly illustrated in Figs. 1 and 21 of the drawings.

In accordance with the construction provided by the present invention, a suitable means is provided mounting the electrode M on the case 41 of head Q, preferably at the lower end of the case and in the drawings this construction is shown as including a yoke 160 depending from case 41 and carrying a pivot pin 161 that pivotally carries the upper end of the plate 120 of the electrode M. A suitable means is provided for setting or stopping the electrode to the desired position about the axis of pin 161. In the construction illustrated, suitable stops 162 are carried by the depending yoke 160 and are located to engage opposite sides of the plate 120, as clearly illustrated in Fig. 21. Through this construction, by setting or ad-

justing the screws 162, the electrode M can be set to extend downwardly and inwardly toward the axis of the spindle N, and the particular angle of the electrode can be varied, as circumstances may require.

The supply means R is provided to handle a suitable supply of welding material, that is, a suitable supply of wire or welding rod 35. In the particular construction illustrated, the means R includes an upwardly projecting yoke 170 on the case 41, which yoke carries a pivot 171 supporting a reel 172 carrying a suitable supply of wire or rod 35. The rod 35 from the reel 172 extends down from the reel to and through the case 41 to enter the electrode M, and, in the preferred construction, a suitable means is provided to straighten the rod as it issues from the coil on reel 172 to the mechanism handling it, as it passes to the point where it is used. In the particular case illustrated, the rod-straightening mechanism includes a pair of guide rollers 175 between which the rod passes as it proceeds from the reel, and spaced rollers 176 spaced along the rod and at opposite sides thereof in a manner such as is indicated in Fig. 21 of the drawings.

In accordance with the general arrangement and proportioning of parts, the extension 147 of the carriage O depends a substantial distance below the rails 23 and the body 146 of the carriage O, so that the reel 172 carried by means R is supported in a position laterally offset from the extension 147 and in a vertical position, so that it will clear or pass with clearance beneath the rails 23 as the spindle end is rotated through a complete circle. The general relationship of parts just referred to is clearly illustrated in Fig. 1 of the drawings.

The rod feeding means S, which may be any suitable mechanism of this type, is carried by case 41 of head Q and, in the preferred construction, the means S includes a suitable mechanism within the case 41 engaging the rod as it passes through the case. Means S is shown as including a prime mover or motor 180 mounted on the exterior of case 41 to drive the mechanism located within the case. In practice, any suitable rod or wire feeding mechanism can be employed in carrying out the present invention, and for this reason, this portion of the mechanism is indicated generally.

The means T provided for operating the carriage O, that is, for reciprocating it, is preferably a power means, and it is shown as a fluid pressure actuated means involving a cylinder and piston mechanism, the cylinder 181 of which is fixed to the beam 22 of the frame, while the piston rod 182 connected to the piston of that mechanism and projecting from the cylinder 181 is connected to the carriage O by a suitable coupling 183. This construction is best illustrated in Figs. 15, 18 and 20 of the drawings. The stop means T' includes opposed stops 183^a, preferably screws, carried by the beam 22 and located to be engaged by the carriage at each end of its stroke. By adjusting the screws the stopping positions of the carriage O can be set as desired.

The drive means U provided by the present invention to turn the spindle N and thereby operate it through a predetermined cycle relative to the carriage O is shown in the drawings as including a round flange 185 fixed on the spindle above the body portion 146 of carriage O, and at a point where it is within the beam 22 of frame A. A plurality of circumferentially spaced pins 186 are carried by the flange 185 and are shown as projecting upwardly therefrom, and each pin is preferably in the nature of a roller, as shown in the drawings. A pusher 187 is operated by a suitable means 188 to move relative to the spindle, and is adapted to engage and push the pins 186 and thereby effect the desired rotation or turning of the spindle.

In the mechanism provided by the present invention, the pusher includes a block or head 199 carried on a reciprocating rod 200, and it includes a bell crank mounted on the head 199 by means of a pivot pin 201. The bell crank has a pusher arm 202 and a stop arm 203. The

pusher arm 202 of the bell crank is carried so that its outer or terminal end 205 moves or reciprocates tangentially of the spindle when the rod 200 is reciprocated, and it is related to the pins 186, so that, as the rod 200 moves out or in the direction indicated by the arrow in Fig. 16, the end 205 of arm 202 engages a pin 186 and pushes it in the direction indicated by the arrow (curved arrow) in Fig. 16, with resulting turning of the spindle.

When the rod 200 is returned or retracted as by movement in the direction indicated by the arrow in Fig. 17, the arm 202 of the bell crank is retracted or moved back and will drag and lift over a pin 186 in its path, in the course of which action the bell crank pivots about the pin 186, as will be apparent from a consideration of Figs. 16 and 17 of the drawings. When the rod 200 and therefore the arm 202 of the bell crank reaches a completely returned or retracted position, the bell crank returns to a normal position where the end 205 of arm 202 is directly opposite a pin 186, namely, the pin over which the arm has just dragged or rocked, so that between the next movement or advance of the rod 200 and arm 202, that pin is engaged and operated to effect turning of the spindle.

The stop arm 203 serves as a means by which the action of the push arm 202 of the general relationship of the parts is suitably set and limited. A spring 210, preferably a tension spring, anchored as at 211, is connected to the stop arm 203 and normally tends to move the bell crank to a position where the push arm 202 is positioned to engage and operate a pin 186 as the pusher is advanced. A stop member, preferably a screw 212, is carried by the head 199 of the pusher to limit the return or positioning of the bell crank under action of spring 210, and, being a screw, it is adjustable to accurately set or determine this positioning of the bell crank.

An adjustable screw stop 213 is carried by the stop arm 203, and it is located and projects from arm 203 to be engaged by a pin 186 and thereby stops turning of the spindle when the pusher has been fully advanced and the action of arm 202 has been completed.

The means or mechanism provided for operating the rod 200 is preferably a fluid pressure actuated mechanism and is shown as including a cylinder 215 fixed to or carried by the carriage O and the rod 200 is the piston rod of this cylinder and piston mechanism, as will be apparent from a consideration of Figs. 15, 16, 17 and 18 of the drawings.

In the particular form of the invention under consideration, that is, where the machine is handling the particular work that has been described it is preferred that the spindle N be turned through exactly 90° each time it is operated by the drive U. In this case, the mechanism of means U as above described is established with four equally spaced pins 186 on the flange 185, and the mechanism is operated and set so that each time the fluid pressure actuated mechanism of means U operates, it effects an advance or turning of the spindle N through exactly 90°.

The flux or supply means V as provided by the present invention is a mechanism serving to supply flux to the work immediately before the arc for welding is struck, and it continues to supply flux to the work as the machine operates, to the end that the arc that is struck and which is maintained during the welding operation is submerged in or flooded by means of flux, to the end that there is an ample supply of flux present for welding and oxygen is excluded from the weld to prevent burning of the metal.

The structure of means V as shown in the drawings includes a flux reservoir 220 supported from the frame, as by legs 221 projecting up from the beam 22 of the frame, so that the reservoir is located well above the point where the flux is to be delivered. A supply duct 222 extends from the conical bottom 223 of reservoir 220 to the upper end of the spindle N, and is preferably

a flexible duct maintaining the desired connection between the reservoir and spindle throughout movement of the spindle, resulting from reciprocation of the carriage **O** supporting the spindle. At the upper end of the spindle the supply duct **222** empties into funnel **343** that opens into the spindle. At this point there is provided a flux control valve **226** adapted to be operated by a suitable electromagnetic operating unit **228**. The valve is opened under control of a timer in the control system so that it passes a given amount of flux each time it is operated, which amount is such as to properly flood the arc with flux as the machine goes through its cycle. Further, in the particular case illustrated, an agitating means in the form of a vibrator **229** is shown in connection with the parts just described, to prevent choking or clogging, and to assure free flow of flux from the reservoir to the spindle when the valve **226** is open.

The flux supply means further includes a vacuum pump **230** connected with the upper end of the reservoir **220**, which is a closed reservoir, by means of a suction line **231**, which suction line is under control of a valve **232** adapted to be operated by an electromagnetic operating unit **233**. A pick-up duct **234** in the form of a flexible hose extends from the upper end of reservoir **220** to a point near the work where it is open or has an open end. The pick-up duct is adapted to be manually operated, and when the valve **226** is closed, there is a reduced pressure established in duct **234** so that the operator of the machine, by suitably manipulating the open end of the duct **234** can pick up free or excess flux so that it is returned to the reservoir. In practice, a suitable screen **240** is provided in the reservoir. In practice, a suitable screen **240** is provided in the reservoir, so that, as flux is returned to the reservoir, it will screen out foreign matter which may have been picked up.

A flux delivering duct **241** is provided and extends from the lower end of the spindle to the tip end portion of the electrode **M**, where it is fixed and serves to discharge flux passed when the valve **226** is open. The delivery end of duct **241** is so related to the tip of the electrode as to deliver flux to the work so that, when the welding arc is struck, it is submerged in flux and the delivery of flux precedes the arc as the operation of the machine proceeds, so that the arc remains submerged at all times.

The welding circuit included in the machine may, in a typical situation, involve a D. C. circuit energized by a motor generator set or the like, and in the particular machine under consideration, the electrode **M** by reason of its insulated mounting on the spindle **N** is an electrically insulated element energized by the line **126** carrying one side of the welding circuit. The other side of the welding circuit may, in effect, be grounded by a line **251** to an element of the structure with which the work is contacted, for example the base **20**. In the particular case illustrated a flexible connection **251^a** connects the base **20** and table **24**, and a flexible connection **251^b** is shown connecting the table **24** and the jaw **28** that engages the work located in fixture **C**.

The construction illustrated in Figs. 35 to 40 inclusive varies somewhat from that hereinabove described and in particular it is characterized by a table having a slide operating transversely thereof, which slide is adapted to carry two groups or units of work parts, one in the course of being welded upon and the other arranged preparatory to being welded. In the structure shown in Figs. 35 to 40 inclusive, there are other variations in details of construction as will be apparent from comparisons of the drawings. Further, it is to be noted that in Fig. 35 the head **Q** carrying the electrode is mounted on the spindle **N** by means of an arm **40^a** whereby angular adjustment of the head can be gained to effect desired setting of the welding rod relative to the work.

In the construction as shown in Figs. 35 to 40, the table **24** supported on base **20** is provided in its forward end

portion with an enlargement **24^a** elongate in form and disposed transversely of the table. Further, the table **24** at the enlarged forward and portion **24^a** thereof is provided with a slide **300**. A suitable means **301** supports the slide **300** on the enlargement **24^a** of table **24** so the slide can be reciprocated transversely of the table. In the construction illustrated, spaced rails **302** are carried by the enlargement **24^a** of table **24** to extend longitudinally thereof and hence transversely of the table. Suitable mounting rollers **304** are carried by the slide and cooperatively engage the rails.

In the form of construction now under consideration, the rest **25^a** having a top face **60** adapted to receive work, is integrally joined to the slide **300** so that it is in effect a part of slide **300**, and the slide and its rest portion **25^a** is of substantial length as clearly illustrated in Fig. 39 of the drawings.

The rest **25^a** includes a ridge **61** extending longitudinally of the rest to cooperate with the retainer **26** in the manner hereinabove described. With the form of construction under consideration, when slide **300** is at one end of its stroke, say, for instance, when it is positioned as shown in Fig. 40, work parts located on the rest **25^a** at the right hand end portion thereof are in position to be engaged by the single retainer **26** mounted on table **24** to reciprocate longitudinally thereof. While the work parts on the right hand end portion of the rest are being worked upon or welded, other work parts can be arranged on the left hand end portion of the rest so that when the rest is moved to the right hand end of its stroke, the welded parts are moved out so they can be removed as desired, while the work parts on the left hand end portion of the rest are in a position to be engaged by retainer **26**.

A means **310** is provided to operate or reciprocate the slide so that it is shifted between the positions just described. In the construction illustrated, means **310** includes a fluid pressure actuated means or mechanism having a cylinder **311** fixed as to the base **20** while the piston rod **312** thereof extends horizontally and connects to a depending arm **313** on the slide **300**. A valve **380** is provided to control the action of the means **310**, as will be hereinafter described.

In the preferred construction, an abutment member **315** is carried by the table **24** and suitable projections **316** on the slide are opposite the member **315** when the slide is at the ends of its stroke. Through this construction, when the clamp **26** is operated to engage the work and clamp it forward against the ridge **61**, or a jig, if such is used, the work supporting rest and the slide **300** on which it occurs are effectively backed up and held against forward movement.

In the particular construction illustrated, a suitable adjustable stop means and shock absorber **325** is provided to stop the clamp carriage **31** at the rear or retracted end of its stroke, and this is shown as a hydraulic pressure actuated shock absorber engaged by a bracket **326** carried on the clamp carriage. Further, in the form of the invention under consideration, an adjustable stop means **330** is provided in connection with stem **29**, and the construction illustrated includes a yoke **331** carried by the clamp carriage **31** and a stop screw **333** carried by the yoke and engageable with the upper end of the stem **29**.

In the form of construction under consideration the arm **40^a** carrying head **Q** which supports the electrode instead of being directly supported on the spindle **N** by an arm as shown in Fig. 1, is provided with an arcuate arm **40^b** provided by a slot **40^c**. Suitable clamp means **40^d** carried by a block **40^d** engages in the sloped arm **40^b**, which block is carried by the spindle, preferably through insulation as described with reference to arm **40** in the form of construction first described. Through the construction just described, the head **Q** is supported from spindle **N** so that it can be suitably adjusted to vary the angle to which the electrode **M** is related to the work.

In the preferred form of the invention, the flux valve 226 is a ball type valve in which a ball of rubber, or the like, controls flow of flux through a tubular element 341. The flux that flows or which discharges when valve 226 is open enters a suitable receptacle, preferably a funnel-like receptacle 343, and flows from there into the duct that extends to the work. In accordance with the invention, as will be hereinafter described, the operator 223 that operates valve 226 acts under control of a timer so that when the valve is opened or operated, it remains open a predetermined length of time with the result that a predetermined amount of flux is passed and the action is adjusted so that the amount of flux passed is sufficient to supply flux to the work continuously as the arc operates to carry out the welding operation.

It will be immediately apparent from the drawings that the particular details of construction as set forth in Figs. 35 to 40 inclusive, may, in practice, be carried out to advantage in the general machine construction set forth in Figs. 1 to 35 inclusive, and it will be apparent that variation from one form or type of machine to the other involves but slight modification or change that can be readily carried out as circumstances may require.

The hydraulic system X as provided by the present invention and as illustrated in Fig. 41 of the drawings is under control of the electrical control system illustrated in Figs. 42 to 44 of the drawings, and in general, it includes a fluid pressure supply, manifolds and control valves connected with the manifolds and responsive to the electrical control system. The system suitably controls the action of the fluid pressure controlled mechanisms hereinabove described. The hydraulic system X is or may be substantially the same insofar as the different forms of construction above described are concerned, and, therefore, the following description of a typical embodiment of the hydraulic system is to be understood as applicable to both forms of construction insofar as it is required.

The fluid pressure supply of system X in practice may involve a reservoir 255 carrying a suitable supply of fluid, say, for instance, oil. A prime mover, preferably an electric motor 256, is provided to operate pressure generating means, and in the case illustrated, the motor 256 drives pumps 257 and 258, each of which has its intake connected to the reservoir 255 to receive fluid therefrom.

The pump 257 delivers fluid at a suitable pressure to a manifold 259, while the pump 258 delivers fluid at a suitable pressure to a manifold 260. The pump 257 delivers fluid at a pressure greater than that delivered by pump 258, and the manifold 259 may therefore be considered a high pressure manifold, and the manifold 260 is a low pressure manifold. In practice, the pressure maintained in manifold 259 is in the neighborhood of about 210 lbs. per square inch, whereas that maintained in manifold 260 is about 160 lbs. per square inch. A suitable pressure regulator 261 is provided to regulate the pressure from pump 257 so that a constant, or substantially constant, pressure is maintained in manifold 259 while a pressure regulator 262 is provided to regulate the pressure from pump 258 so that a constant, or substantially constant pressure is maintained in manifold 260.

In the line 259^a from the pressure regulator 262 to manifold 260, there is an air accumulator 260^b with a surge tank 260^c suitably related thereto, and between the accumulator 260^b and the manifold 260, there is a main control valve 263. In the case of the high pressure system, a suitable main control valve 264 is provided in the line 259^a connecting the regulator 261 and manifold 259.

A suitable exhaust manifold 265 is provided and is connected with the reservoir and a suitable back pressure valve 370 is provided between the manifold and reservoir 255, so that there is at all times a suitable predetermined back pressure maintained in the hydraulic system.

In accordance with the present invention, the main valves 263 and 264 are operated, so that they are opened only when the pumps are operated with the result that the hydraulic system is at all times maintained filled or loaded.

5 In the arrangement illustrated generally in Fig. 41, a two-way or reversible valve 266 controlling carriage O is connected by a line 261 with the low pressure manifold 260 and by a line 267 with the exhaust manifold 265 and lines 268 and 269 connect the valve 266 with cylinder 181. An adjustable flow control or regulator 266^a is provided in line 267 so that the speed of operation of carriage O is suitably controlled. When valve 266 is in one position, the fluid pressure actuated mechanism of means T is operated to one position, and when the valve 266 is reversed, that mechanism is operated to the other or opposite position.

10 A two-way or reversible valve 270 is connected by a line 271 with the high pressure manifold 259 and by a line 272 with the exhaust manifold 265. Valve 270 is connected with the fluid pressure actuated mechanism 183 of drive means U by connections or lines 273 and 274, so that when the valve 270 is in one position, the mechanism 183 is operated to one position, and when the valve 270 is reversed, the mechanism 183 is operated to the other or opposite position. An adjustable flow control or regulator 270^a is provided in line 271 so that the speed of operation of mechanism 183 is suitably controlled.

15 A two-way or reversible valve 275, which is normally in one position, is connected by a line 276 with the low pressure manifold 260 and by a line 277 with the exhaust manifold 265 and is connected with the fluid pressure actuated mechanism of means F by connections or lines 278 and 279. When valve 275 is in one position, the mechanism of means F is operated to one position, and when valve 275 is closed, this mechanism is operated to the opposite position. An adjustable flow control or regulator 275^a is provided in line 279 so that the speed of operation of means F is suitably controlled.

20 A two-way or reversible valve 280, which is normally in one position, is connected by line 281 with the low pressure manifold 260 and by line 282 with the exhaust manifold 265, and is connected by lines 283 and 284 with the cylinder of the fluid pressure actuated mechanism of means I. An adjustable flow control or regulator 280^a is provided in line 283 and a check controlled by-pass 261^b is provided around regulator 280^a so that the regulator is effective only when the stem 29 is moving upwardly. When valve 280 is in one position, said mechanism of means I is operated to one position, whereas, when the valve 280 is reversed, said mechanism is operated to the other or opposite position.

25 A two-way or reversible valve 285, which is normally in one position, is connected by line 286 with the low pressure manifold 266 and by line 287 with the exhaust manifold, and lines 288 and 289 connect the valve 285 and the fluid pressure actuated mechanism of means J. An adjustable flow control or regulator 285^a is provided in line 289 and a check controlled by-pass 286^b is provided around the regulator so that the regulator operates only when the carriage 31 is moved rearward. When the valve 285 is in one position, said mechanism of means J is operated to one position, whereas when the valve 285 is reversed, said mechanism of means J is operated to the opposite position.

30 A two-way or reversible valve 290 is connected by line 291 with the manifold 260 and by line 292 with the exhaust manifold 265, and is connected by lines 293 and 294 with the cylinder 74 of the fluid pressure actuated mechanism of means E. An adjustable flow control or regulator 290^a is provided in line 292 to control the speed of operation of the table in both directions. When the valve 290 is in one position, said mechanism of means E is operated to one position, whereas, when the valve 290

is reversed, the said mechanism of means E is operated to the opposite position.

When the machine is provided with the slide 300 a two-way or reversible valve 380 of means 321 is connected by line 381 with the manifold 260 and by a line 382 with the exhaust manifold. Lines 383 and 384 connect the valve with the cylinder 322 which operates the slide 300. Adjustable flow controls or regulators 386 and 387 each acting in one direction only are connected in lines 383 and 384, respectively, so that the speed of operation of the slide is controlled in both directions.

The electrical control system Y as illustrated in Figs. 42 to 45 inclusive is but a typical, simple type or form of control system that may be employed in the machine to effect the desired control or operation of the various elements of the system X, as illustrated in Fig. 41, to the end that the machine, when set in motion or operation, carries out a predetermined action or cycle of operation. The particular system illustrated is intended to effect continuous operation of the machine until such time as it is turned off, as will be hereinafter described.

With a machine embodying the present invention as hereinabove described, and having a hydraulic system such as has been described and illustrated, the cycle of operation can, in practice, be varied considerably as circumstances may require, and, in practice, it can even be varied with reference to any particular work to be handled. For example, the particular cycle of operation may be varied somewhat to advantage, depending upon whether the machine is of the type first described, or of the type last to be described, that is, whether the machine has a table without a slide, or whether it has a table with a slide.

If, for example, the machine is of the type first described, that is, of the simple form, without a table having a slide, the cycle may be advantageously set so that parts in starting position are related, as illustrated in Figs. 1, 6 and 21 of the drawings.

In the starting position the spindle N is in the rotative position illustrated in Figs. 1 and 21 of the drawings, thus locating the terminal end of the welding rod 35 as shown in said figures and as indicated in full lines in Fig. 30 of the drawings, and in dotted lines in Fig. 28 of the drawings. In this starting position the table 24 of carrier B is forward, as illustrated in Fig. 6, and the retainer 26 of fixture C is retracted or rearward of the rest 25, as shown in Fig. 6, while at the same time the stem 29 of means H is elevated, holding the jaw 28 of the clamp G in an up position, the carrier 31 of means H being in a rear or retracted position so that the jaw 28 is rearward of the fixture C.

When the operation of the machine is initiated as by the manual closing of a starting switch 400, means F is operated as by actuation of valve 275 and means J is operated as by working of valve 285, so that the stem 84a carrying retainer 26 is moved forward relative to table 24 until the fingers 64 of the retainer overlie the blades 10 and until part 63 abuts the blades, clamping them against ridge 61. The valve 275 controlling means F remains positioned so that pressure remains on means F, so that retainer 26 remains in holding or clamping position relative to the work throughout the remaining operation of the machine, or until the end of the cycle of the operation, as will be hereinafter described.

The working or operation of means J resulting from working of valve 285 results in forward movement of carrier H relative to table 24 until the jaw 28 overlies the work in fixture C. Pressure remains on means J so that carrier H is held forward. When the parts are thus positioned, valve 280 controlling means I is operated, causing downward movement of stem 29 and consequent lowering of the jaw 28 into working engagement with the bodies 11 of the caps, and pressure is maintained in means I holding the jaw in pressure engagement with the work. With the work thus clamped or held, it is

effectively electrically grounded to the table 24, which is in the grounded side of the welding circuit.

With the work held ready for welding, the valve 226 controlling flux is opened for a predetermined length of time so that a given amount of flux from the reservoir 220 is passed for delivery to the work to submerge the projecting tip end of the rod from electrode M as the welding operation is carried out. When this has occurred, switch 410 operated by arm 30 and controlling the welding circuit closes and the welding operation starts by first feeding the rod into contact with the work whereupon the released flux reaches and submerges the rod after which the rod is energized and then picks up to start the arc that effects the welding.

The initial welding occurs at what may be considered the right rear corner of the work. Simultaneously with the start of welding, the means E is set in operation by working of valve 290, and as a result, the table 24 is put in operation so that it moves rearwardly, carrying the work rearwardly relative to the rod. This operation continues until this table reaches the rear end of its travel and the parts have reached a position where the rod carried by the electrode is at the front right hand corner of the work, whereupon the mechanism 188 of drive U is energized, causing the spindle N to turn through an angle of 90° to bring the welding rod 35 into the position shown in full lines in Fig. 28, and means T is put in operation by the working of valve 266 so that upon the rod reaching the position shown in full lines in Fig. 28, the carriage O is put in motion transversely of the table 24 and is moved to the left relative to the table, with the result that the welding occurring between the cap body at the right and the blade at the right continues lengthwise of the blade, it being understood that as the preceding operation occurred, welding Z was established joining the end 16 of the body 11 to the blade, as shown in the drawings.

The valve 266 remains positioned so that the carriage O is fed or operated to the left as the welding continues from the cap body 11 at the right to and along the cap body at the left until the welding rod 35 reaches the left forward corner of the work at which time valve 266 is closed, stopping further movement of carriage O, and valve 270 is operated, causing another operation of mechanism 188 of drive U with consequent turning of spindle N through 90° to position the welding rod at the left hand end of the work ready to weld along the end 16 of body 11 at the left. As the rod is thus turned at the front left hand corner of the work, the valve 290 controlling means E is reversed, with the result that the table 24 moves forward and continues to move forward until the table reaches the forward end of its stroke, at which time the rod 35 is at the left rear corner of the work.

As the table moves forward to effect welding along the left end of the work, the valve 280 controlling means I is reversed and the valve 275 controlling means F is reversed, with the result that the clamp jaw 28 is lifted from the work and the carrier 29 is moved rearwardly relative to the table, returning these parts to the initial or starting position. When the welding rod reaches the left rear corner of the work, and after the weld being applied to the work has thus continued along the right hand end of the work, the forward side of the work, and then along the left hand end of the work, valve 270 controlling mechanism 188 of drive U is operated, causing the spindle N to be turned through 90° so that the rod is correspondingly swung around or turned relative to the work ready for welding along the rear edge of the work. At this time in the cycle of operation, valve 266, controlling means T is reversed, setting the carriage O in operation so that it moves toward the right with consequent procedure of weld along the rear edge of the work until the weld is completed up to the right rear corner of the work where the weld started. The move-

ment of the spindle can terminate here, as hereinafter pointed out, or as in the case being described, the valve 270 controlling mechanism 183 of drive U can be again operated to effect movement of the spindle N through 90° to bring the rod into the position from which it started operation as shown in Figs. 1 and 6. At this point in the cycle the switch 419 controlling the welding circuit is opened, and the welding operation is completed. As the welding operation terminates, valve 275 is operated so that the retainer 26 is retracted from 10 the work.

In the case of the machine wherein the table is equipped with a slide operating transversely thereof, the operator of the machine applies work to the fixture at the end of the slide remote from that carrying the work acted upon in the course of operation of the machine, and when the welding operation has been completed and following withdrawal or retraction of the retainer 26, switch 411 is closed, effecting operation of valve 380, which results in movement of the slide relative to the table shifting the welded work out from operating position and the newly applied work into welding position.

The valve 226 controlling the flow of flux to the work is opened under control so that it releases enough flux to maintain flow of flux continuously to the work as welding occurs with the result that the welding rod is kept submerged in flux until the weld is completed.

It is to be understood that, as the operation of the machine proceeds as hereinabove described, the rod feeding means or mechanism S carried in case 41 of head Q is operated, causing the welding rod 35 to be fed to the work at the desired rate. The driving or energizing circuit to the motor 189 operating the feed mechanism S is communicated to the motor through a commutator type mechanism occurring at 350, which mechanism includes annular contacts 351 on the spindle within the extension 147 of carriage O, and brush contacts 352 suitably insulated and carried by the extension 147 to engage and cooperate with contacts 351. In practice, it is preferred that the motor 189 be of the type commonly employed in connection with a welding rod feed such as is shown in the drawings, to the end that the feed of welding rod is properly coordinated with the welding action, and in such case the commutator mechanism 350 includes a plurality of related contacts carrying the desired circuits to the necessary parts of the motor 189 such as the field as well as the armature.

In carrying out the invention, a line extends from the generator to a commutator mechanism 370 at the spindle where it connects with a brush 371 of the mechanism 370 supported by suitable insulation 372. The brush 371 contacts a ring type contact 375 mounted on the spindle by means of insulation 376, and the conductor 126 or section of said line continues from the ring contact 375 to the electrode M, as hereinabove described.

In setting the cycle of the machine, when the machine is equipped with a slide on the table 24 supporting the work-holding fixture for movement laterally as well as longitudinally relative to the base of the machine, it is preferred to set the mechanism so that the cycle of operation starts with the spindle N holding the head Q in a position where the rod 35 extends down and forward. Under this condition or setting, as the cycle starts the starting operations above described occur, and in addition thereto, the spindle N is initially rotated through 90° before the arc is struck. Further, there is something of a variation in the cycle at the end thereof, that is, the cycle stops with the spindle N in position so that the rod 35 extends down and forward instead of making the turn at the rear right corner as in the case of the cycle above described.

The electrical control system provided by the present invention includes generally suitable electromagnetic actuating units for or in connection with the several valves of

the hydraulic system and suitable switches and the proper electrical connections.

Considering the electrical control system more specifically, it is significant to observe that the electro-magnetic operating units or operators of the electrical system related to the valves of the hydraulic system and certain other elements of the electrical system are illustrated in Figs. 44 and 45 separate and apart from the balance of the electrical system, in that these parts are, in practice, such that they can be advantageously coupled to the other elements of the system through suitable releasable connectors or jacks which are indicated in Figs. 42 and 43.

In like manner, the parts or elements shown in Fig. 44 being the parts making up the manual control incorporated in the system, are shown separate from the other parts of the system, and are connected thereto by suitable jacks. Further, in Fig. 45 of the drawings, there are illustrated elements of the electrical system such as can, in practice, be advantageously employed at an instrument board provided at an accessible part of the machine, and these elements are adapted to be connected by means of jacks with the other elements of the system.

Throughout the figures of the drawings illustrating the electrical system, like conductors or terminals, that is to say, corresponding electrical elements or ones that are connected in common, bear like, or common, identifying marks, and for simplicity of illustration, the necessary lines or connections incidental to joining such corresponding or connected parts have been eliminated.

Assuming the machine is set to carry out the cycle with the rod 35 starting from a downward and forwardly extending position, and assuming the table 24 to be in a forward position while the clamp jaw 28 is up and in a rear position, and the retainer 26 in a rear position, the electrical system is put into action by closing of starter switch 400. Closing of switch 400 energizes relay MMM and simultaneously energizes a spindle and clamp delay timer TD8 and relay JJJ.

The energization of timer TD8(5) effects energization of operator 403 of valve 285, starts forward movement of the carriage supporting the stem 29 that carries the clamp jaw 28 which is to engage the work. When the clamp jaw has reached its forward position, it energizes or trips a limit switch AA, which results in energization of relay FFF, which in turn energizes relay CCC.

The energization of relay FFF results in energization of operator 404 of valve 280 so that stem 29 is moved down until the jaw 28 engages and clamps the bodies 11 of the tooth caps onto the blades 10 thereof, which in turn results in the blades being held tight and in grounded contact with the rest 25.

The closing of relay CCC sets that relay so that it is held closed through a limit switch JJ and through relay NNN, which switch and relay are in series. Closing of relay CCC results in energization of flux delay timer TD2(5) and arc delay timer TD4.

The flux delay timer TD2 acts through relay NNN and rod extractor timer TD6(7), making TD6 ready for operation. The operation of timer TD2(6) and (8) effects energization of flux timer TD3, which in turn energizes relay TTT setting actuators 228 and 233 in operation, so flux valve 226 is opened and the vacuum valve 231 is opened. The energization of arc delay timer TD4 through relay CCC makes up contacts 5 and 7 of TD4, and through relay NNN and arc starter timer TD5(3) and (7), it energizes relay AAA, contacts 3 and 5, closing contacts 14 and 15 of table start timer TD1, thereby starting the table start timer.

Through the timers, the energization of the welding circuit to strike the welding arc is given a slight lead over movement of the table. The energization of relay AAA, contacts 3 and 5 effects closing of the main relay of the welding circuit, that is, the D. C. circuit, with the result that the welding action is initiated.

The present invention is in no way concerned with details of the D. C. circuit included in the machine and those parts of the machine will therefore be referred to in but a general way, it being understood that any ordinary or conventional welding circuit may be employed, so long as there is a proper feeding and retraction of welding rod and energization thereof, to the end that the desired weld occurs as the machine is operated.

When the timer TD1(5) and (7) is energized, relay GGG is energized through relay NNN, so that actuator 405 is de-energized and actuator 406 is energized, resulting in operation of valve 290 so that the table 24 starts to move rearwardly and continues to so move until it reaches the end of its stroke.

When, as a result of the action hereinabove described, the spindle N has reached the end of its initial movement, that is, when it has been operated through 90°, a limit switch QQ is opened, resulting in operation of valve 270 controlling mechanism 188 so that mechanism 188 returns the pusher to the initial or unactuated position.

As the table 24 reaches the end portion of its rearward stroke, it closes limit switch DD, which through relay NNN energizes relay HHH, opening contacts 52x of HHH and closing contacts 51x of HHH, with consequent actuation of operator 413 so valve 266 operates, causing carriage O to move toward the left.

As the table 24 reaches the rear end of its movement or stroke, limit switch HH is closed, energizing limit switch timer TD10, which acts through relay QQQ so that actuator 402 of valve 270 is operated with consequent turning of the spindle N through its second movement of 90°, thereby causing the rod 35 to be moved around at the forward right hand corner of the work.

As the carriage O reaches the end of its stroke to the left, it operates limit switch EE, causing operation of relay GGG with consequent closing of contacts 47x of GGG, so that line L1D is energized, thereby resulting in operation of actuator 405. This operates valve 290 so that the table 24 is started forward.

Simultaneous with the closing of limit switch EE, the carriage O operates limit switch NN, thereby actuating limit switch timer TD10, which, through relay LLL, operates actuator 402 of valve 270, with the result that the spindle N is operated through mechanism 180 to make its third movement through 90°. Upon the completion of the third movement through 90° of spindle N, limit switch QQ is operated as occurred at the termination of the second movement of the spindle, with the result that the pusher that actuates the spindle is returned to its normal or unactuated position.

In the course of its forward movement, table 24 operates limit switch FF, which, through relay NNN operates relay FFF, which up to this time has been operating so that the work-holding clamp was held down. The operation or de-energization of relay FFF results in operation of the operator 404 of valve 280, to effect lifting of the stem 29 that carries the jaw 28, so that the jaw leaves the work.

When the jaw reaches a predetermined elevated position, it operates limit switch CC, causing the valve 285 to be operated through actuator 403, so that the carriage supporting the stem that carries the jaw is moved rearwardly. This operation of the parts mentioned results in the jaw being up and back out of the way of the electrode M, and the rod 35 carried thereby, so that the head Q carrying the electrode M is free to be swung through its final 90° at the left rear corner of the work, when the table 24 reaches the forward end of its movement, and the way is clear for the movement of the carriage O necessary to effect welding along the rear edge of the work.

The table 24 as it reaches the forward end of its stroke operates limit switch GG, which through relay NNN actuates or drops out relay HHH, closing contact 52x and line L1D of relay HHH, and opening con-

tact 51x and line L1D, of that relay, so that actuator 412 operates valve 266, thereby setting the carriage O in movement to the right.

The table as it reaches the forward end of its movement or stroke operates limit switch HH, which through limit switch timer TD10 operates relay LLL so that actuator 402 operates valve 270, causing operation of mechanism 188 to effect turning of the spindle N through its last movement or through its last 90°. At the termination of the full operation of mechanism 188, limit switch QQ is actuated, with resultant return of the mechanism 188 to its unactuated position.

At the end of the movement of the carriage O to the right it operates limit switch JJ, which in turn causes actuation of relay DDD, the operation of which cuts out the welding circuit and causes operation of relay SSS which operates the rod extractor timer TD6 and the retainer timer TD7. Operation of the rod extractor timer TD6 results in retraction of the welding rod 35 from the work and operation of the retainer timer TD7 results in operation of relay JJJ, causing actuator 401 to be operated, causing valve 275 to operate so that the retainer 26 is moved rearwardly away from the work and finally to its retracted position.

As the retainer 26 reaches its retracted position, it operates slide switch 411 which effects operation of relay KKK so that operator 419 is actuated, causing valve 380 to be operated, so that slide 300 is put into operation and moves transversely of the table 24, moving the completed welded work out from its position beneath the spindle N and moving the newly applied work into position beneath the spindle ready for the next operation of the machine.

As the operation just described occurs or is completed, a starting switch, either starting switch KK or starting switch LL is operated by the slide. Each of these starting switches is parallel with the starter switch 400 and initiates a new cycle of operation. The switches KK and LL are both in parallel relation with the main starter switch 400 and they are located to be operated alternately, that is, one when the slide is at the left hand end of its stroke, and the other when the slide is at the right hand end of its stroke.

In the preferred embodiment of the invention, a control is provided to effect disengagement of the switches KK and LL from the system if it is desired that the machine operate through but one cycle at a time, with resulting stoppage at the end of each cycle, and requiring manual initiation of each cycle. This cut-out for the switches KK and LL involves a selector switch 420 connected in the circuit as indicated in the diagram. Under normal operating conditions, the selector switch is set so that switches KK and LL are in service with the result that the machine continues to operate through one cycle after another, until it is deliberately cut out of service by opening of the selector switch 420.

In Fig. 44, manually operable switches are illustrated which switches are available for operation of the valve actuators manually, so that the machine can be so operated when necessary, as, for instance, in the course of setting it up ready for action. In Fig. 45 of the drawings, switches are illustrated whereby emergency operations can be performed, as for instance, stoppage when necessary in the course of the performance of a cycle.

In the particular system illustrated there are various manually operable switches which, in practice, are made accessible to the operator of the machine and which, considered generally, are to be used in the setting or adjusting of the machine or, in the event of emergency, as circumstances may require. A switch 500 controls establishing of the system for manual operation and acts through relay NNN so that when it is operated to set the system for manual operation, the various timers and limit switches are cut out. It is preferred that an indicator 75 such as, for example, an indicating light or the like, be

included in the circuit controlled by switch 500 so that the operator of the machine can readily determine whether or not the machine is set for automatic operation or manual operation.

A switch 501 is provided to control operation or action of the clamp G, the particularly forward movement thereof, and acts through a self holding contact of relay MMM. Relay MMM, when operated, acts through a switch 502 and relay NNN and effects opening of the valve 285, the action of which results in forward movement of the clamp. The switch 502 controls movement of the clamp and, more specifically, return movement thereof and opens contacts of relay MMM, effecting operation of the valve 285 which results in reverse or return movement of the clamp. The movements of the clamp just referred to, that is, the forward or reverse movement of the clamp, are affected by operation of carriage 31, which is operable by the means J.

A switch 503 controls the vertical movement of the clamp, and particularly the down movement thereof, and is connected to act through relay FFF which acts through a switch 504 to operate the valve controlling means I so that stem 29 is moved down with consequent downward movement of clamp G. The switch 504 controls vertical movement of the clamp and, more specifically, upward movement thereof and acts through relay FFF to work the valve, which results in upward movement of the stem 29 under the action of means I.

A switch 505 controls movement of carriage O and, more specifically, movement of the carriage to the left, and this switch acts through a relay HHH which in turn is related to switch 506 so that, under action of switch 505, the valve controlling operation of the carriage O is operated so that the carriage moves to the left.

The switch 506 controls the movement of carriage O, and more particularly, its movement to the right, and it acts through relay HHH so the valve just referred to is reversed with resulting movement of the carriage O to the right.

A switch 507 is provided to control operation of the table 24, and more specifically, forward movement of the table. Switch 507 acts through relay GGG and limit switch EE. The action just referred to is through contacts 48 and 84 of limit switch EE and holding contacts 45 to 84 of switch 508 and closed contacts 45 and L1D of relay GGG. When relay GGG is energized, contacts 47 and L1D are open and contacts 46 and L1D are closed so the valve controlling forward movement of the table is operated so that movement of the table occurs. The switch 508 controls movement of the table, that is, rearward or retraction of the table, and it acts through relay GGG to reverse the valve controlling the table so that the desired rearward movement of the table is effected.

A switch 510 is provided controlling movement of the retainer 26. Switch 510 is operable to closed contacts L1D and 53 causing operation of the valve controlling forward movement of the retainer. The switch 510 is operable to another position where their contacts L1D and 53 are open, which results in a reversal of the valve with consequent movement of the retainer rearwardly.

A switch 512 is provided to control operation of the spindle and is self operable to closed contacts L1D and 70 thereby energizing relay QQQ and closing contacts L1D and 71 through limit switch QQ. The relay QQQ closes contacts L1D and 69 resulting in operation of the valve controlling the turning of the spindle. Upon operation or turning of the spindle through 90°, switch QQ is operated, and through relay QQQ, the valve controlling the operation of the spindle is actuated for a return or a retraction of the spindle operating element, making the mechanism ready for another operation or turning of the spindle 93.

A switch 514 is provided to control operation of relay RRR through which the control of operating fluid is

effected. Switch 514 and relay RRR control the valves 263 and 264, which, in turn, control the flow of fluid in the hydraulic system, and when operated effects an opening of the valves so that fluid is supplied to the hydraulic elements. A switch 516 is provided for closing the hydraulic system, that is, to effect the shutting off of the valves controlling the fluid.

A switch 518 is provided and acts through relay RRR to control valves of the hydraulic system, to the end that the system is unloaded or relieved of pressure.

A switch 520 is provided to operate limit switch FF or limit switch PP, but never both of these simultaneously. When switch 520 is operated, contacts 80 and 81 close and contacts 80 and 82 open. Closing of contacts 80 and 81 completes the control circuit through limit switch FF. Lines 81 and 64 are connected through switch FF, and lines 64 and 39 are connected through relay NNN, thus actuating relay FFF. When switch 520 is operated in reverse or oppositely, contacts 80 and 81 open while contacts 80 and 82 close. Closing of contacts 80 and 82 completes a control circuit through limit switch PP and line 82 connects with line 64 through switch PP, and line 64 connects with 39 through relay NNN while relay FFF is operated through line 39.

An emergency switch 525 is provided and is included in the part of the system illustrated in Fig. 45 of the drawings. When switch 525 is operated, the holding circuit to relay RRR is opened, with the result that all fluid pressure is cut off and contact L1D is closed with contact 30. Through closing of contact 30, the welding rod is operated or retracted from the work, stopping welding action.

A switch 526 is provided to effect starting of movements without welding, for instance, an emergency starting in contrast with the stopping effected by switch 525 which may be termed an emergency stop. Switch 526 acts through relay RRR and thereby operates the valves of the hydraulic system so that pressure is established therein, and it opens the holding contacts of relay FFF thereby opening contacts L1D and 37 and results in operation of the valve controlling means 230 so that the clamp is elevated from the work. A switch 420 is provided and controls what may be termed automatic operation of the machine. Operation of switch 420 closes contacts 85 and 87, thus energizing limit switches KK and LL that are parallel with start switch 490, thus acting in the same manner as does, or would, the start switch 490, if actuated. As the machine operates, switch 420 is operated thereby, with resulting automatic operation or continuous repeat of the cycle of the machine until the machine is otherwise taken out of service. A switch 531 is provided controlling flux. Switch 530 closes contacts L1D and 44 and acts through contacts or relay NNN with the resulting energizing of flux timer TD3.

A switch 532 is provided to effect operation that may be termed inching up of the welding rod so that the rod is retracted from the work. Operation of switch 532 closes contact L1D and 30 and acts through relay BBB resulting in operation of the motor that effects movement of the welding rod.

A switch 533 is provided to operate the welding rod which may be termed inching down of the rod. Switch 533 acts through contacts L1D and 31 and relay EEE to operate the motor controlling the rod so that there is an advance or downward movement of the rod.

In the circuit as illustrated, there is a potentiometer for TD3 which may be termed a flux potentiometer and is in the nature of a variable rheostat between lines (9) and (10). Potentiometer TD3 governs the time of operation of the timer TD3.

A potentiometer TD7, that may be termed the clamp potentiometer, is in the nature of a variable resistance and is between lines (9) and (10). Potentiometer TD7 governs the time of operation of timer TD7. There is also included in the machine what may be termed a

generator control, and this, as indicated in the diagram, preferably includes a switch 540 controlling the energization or turning on of the arc. A switch 541 is provided for the turning on of the machine.

The potentiometers TD3 and TD7 are shown in Figs. 42 and 43 which are combined to set forth the over-all electrical circuit, and also in Fig. 45 so as to more clearly set forth their particular relationship.

From the foregoing description of the manually operable controls and emergency equipment, it will be understood that the action of the machine is under full control of the operator. In the foregoing description, the control elements just referred to have been mentioned in general and without specific reference to the details of the particular connections or circuits illustrated in the drawings, since it will be understood that, in practice, variations in such connections or circuits may be made without, in any way, departing from the general spirit of the present invention.

Having described only typical preferred forms and applications of our invention, we do not wish to be limited or restricted to the specific details herein set forth, but wish to reserve to ourselves any variations or modifications that may appear to those skilled in the art and fall within the scope of the following claims:

Having described our invention, we claim:

1. A machine for welding around rectangular work parts having vertically disposed peripheral walls projecting from a horizontally disposed base, including, a table mounted to reciprocate, means adapted to hold a work part on the table, an electrode mounted to turn on a vertical axis and to reciprocate relative to the table and adapted to angularly carry a welding rod with the terminal end thereof at and intersecting said vertical axis and adjacent the peripheral wall of the work part, welding means whereby an arc is established and the rod fed so the work part is welded, and means operating the table and electrode relative to each other in predetermined timed relation whereby the work part and arc move relative to each other establishing straight predetermined lines of welding at the periphery of the work part.

2. A machine for welding around rectangular work parts having vertically disposed peripheral walls projecting from a horizontally disposed base, including, a table mounted to reciprocate, means adapted to hold a work part on the table against movement relative thereto and including a fixture mounted directly on the table and adapted to receive the work part, an electrode mounted to turn on a vertical axis and to reciprocate relative to the table and adapted to angularly carry a welding rod with the terminal end thereof at and intersecting said vertical axis and adjacent the peripheral wall of the work part, welding means whereby an arc is established and the rod fed so the work part is welded, and means operating the table and electrode relative to each other in predetermined timed relation whereby the work part and arc move relative to each other establishing straight predetermined lines of welding at the periphery of the work part.

3. A machine for welding around rectangular work parts having vertically disposed peripheral walls projecting from a horizontally disposed base, including, a table mounted to reciprocate, a slide on the table adapted to reciprocate relative thereto, means adapted to hold work parts on the slide, an electrode mounted to turn on a vertical axis and to reciprocate relative to the table and adapted to angularly carry a welding rod with the terminal end thereof at and intersecting said vertical axis and adjacent the peripheral wall of the work part, welding means whereby an arc is established and the rod fed so the work parts are welded, means adapted to operate the slide relative to the carrier to move work parts on the slide into and out of working position relative to the welding means, and means operating the table and electrode relative to each other in predetermined timed rela-

tion whereby the work parts and arc move relative to each other establishing straight predetermined lines of welding at the peripheries of the work parts.

4. A machine for welding around rectangular work parts having vertically disposed peripheral walls projecting from a horizontally disposed base, including, a horizontally disposed table, means mounting the table for reciprocation, a slide mounted on the table to reciprocate relative thereto, a fixture carried by the slide mounted on the table and adapted to hold work parts, a carrier supported above the table, means mounting the carrier for reciprocation relative to the table, a spindle supported by the carrier to turn on a vertical axis relative thereto, welding means carried by the spindle and adapted to angularly carry a welding rod with the terminal end thereof at and intersecting said vertical axis and adjacent the peripheral wall of the work part, and means whereby the table, the carrier, the slide and the spindle are operated relative to each other in predetermined timed relation to move the work parts relative to the welding means so straight predetermined welds are made at the peripheries of the work parts.
5. A machine for welding around rectangular work parts having vertically disposed peripheral walls projecting from a horizontally disposed base, including, a horizontally disposed table, means mounting the table for reciprocation, a fixture carried by the table and adapted to position a work part, a clamp carried by the table and adapted to move relative thereto into and out of clamping engagement with a work part at the fixture, a carrier supported above the table, means mounting the carrier for reciprocation relative to the table, a spindle supported by the carrier to turn on a vertical axis relative thereto, welding means carried by the spindle and adapted to angularly carry a welding rod with the terminal end thereof at and intersecting said vertical axis and adjacent the peripheral wall of the work part, and means whereby the table, the carrier, the clamp and the spindle are operated relative to each other in predetermined timed relation to move the work parts relative to the welding means so straight predetermined welds are made at the periphery of the work part.

6. A machine for welding around rectangular work parts having vertically disposed peripheral walls projecting from a horizontally disposed base, including, a horizontally disposed table, means mounting the table for reciprocation, a fixture carried by the table and adapted to position a work part, means adapted to clamp a work part at the fixture and including, a carriage on the table and movable horizontally relative thereto, a jaw, and a member carrying the jaw and supported by the carriage to move vertically relative thereto, a carrier supported above the table, means mounting the carrier for reciprocation relative to the table, a spindle supported by the carrier to turn on a vertical axis relative thereto, welding means carried by the spindle and adapted to angularly carry a welding rod with the terminal end thereof at and intersecting said vertical axis and adjacent the peripheral wall of the work part, and means whereby the table, the carrier, the carriage, said member, and the spindle are operated relative to each other in predetermined timed relation to move the work part relative to the welding means so straight predetermined welds are made at the periphery of the work part.

7. A machine for welding work parts including, a table, means mounting the table for reciprocation, a fixture carried by the table and adapted to hold work parts, means adapted to clamp a work part at the fixture and including, a carriage mounted on the table to move relative thereto and parallel therewith, a stem carried by the carriage to move relative thereto, and a jaw mounted on the stem and adapted to be moved by the carriage and stem into and out of position at the fixture and engaging work at that location, a carrier spaced from the table, means mounting the carrier for reciproca-

tion relative to the table, a spindle supported by the carrier to turn relative thereto, welding means carried by the spindle and adapted to handle a welding rod, and means whereby the table, the carrier, the carriage, the stem, and the spindle are operated relative to each other in predetermined timed relation to move the work part relative to the welding means whereby a predetermined weld is made on the work parts.

8. A machine for welding work parts including, an elongate horizontally disposed table, means mounting the table for longitudinal reciprocation, a fixture carried by the table and adapted to hold work parts, means adapted to clamp a work part at the fixture and including, a carriage on the table adapted to reciprocate horizontally relative thereto, a stem shiftably supported by the carriage to reciprocate vertically relative thereto, an arm projecting horizontally from the stem, and a jaw on the arm at a point spaced from the stem and adapted to be operated by movement of the carriage and stem into and out of work clamping position, a carrier supported above the table, means mounting the carrier for horizontal movement relative to the table, a spindle supported by the carrier to turn relative thereto, welding means carried by the spindle and adapted to handle a welding rod, and means whereby the table, the carrier, the carriage, the stem and the spindle are operated relative to each other in predetermined timed relation to move the work part relative to the welding means whereby a predetermined weld is made on the work part.

9. A machine for welding work parts including, an elongate horizontally disposed table, means supporting the table for longitudinal reciprocation, a fixture mounted on the table and adapted to carry work parts, a carriage, means mounting the carriage on the table to reciprocate longitudinally thereof, a stem carried by the carriage to project from the table and reciprocate vertically, an arm carried by the stem and projecting therefrom to approach the fixture when the carriage is in a predetermined position, and a jaw carried by the arm at a point spaced from the stem and adapted to clamp work at the fixture when the carriage is in said position.

10. A machine for welding work parts including, an elongate horizontally disposed table, means supporting the table for longitudinal reciprocation, a slide on the table, means supporting the slide for reciprocation transversely of the table, fixtures mounted on the slide and adapted to be selectively moved by the slide into a predetermined position relative to the table, a carriage on the table, means mounting the carriage to reciprocate longitudinally of the table, a stem shiftably carried by the carriage to reciprocate vertically relative thereto, an arm carried by the stem and projecting therefrom to approach the fixtures in said position when the carriage is in a predetermined position, and a jaw carried by the arm at a point spaced from the stem and adapted to clamp work at the fixtures when the carriage is in said position.

11. A machine for welding work parts including an elongate horizontally disposed table, means supporting the table for longitudinal reciprocation, fluid pressure actuated means adapted to operate the table, a fixture mounted on the table and adapted to carry work parts, a carriage on the table, means mounting the carriage to reciprocate longitudinally of the table, fluid pressure actuated means adapted to operate the carriage, a stem carried by the carriage to reciprocate vertically, fluid pressure actuated means adapted to operate the stem, an arm carried by the stem and projecting therefrom to approach the fixture when the carriage is in a predetermined position, and a jaw carried by the arm and adapted to clamp work at the fixture when the carriage is in said position.

12. A machine for welding work parts including, an elongate horizontally disposed table, means supporting the table for longitudinal reciprocation, fluid pressure

actuated means adapted to operate the table, a slide on the table, means supporting the slide for reciprocation transversely of the table, fixtures mounted on the slide and adapted to be selectively moved by the slide into a predetermined position relative to the table, a carriage on the table, means mounting the carriage to reciprocate longitudinally of the table, fluid pressure actuated means adapted to operate the carriage, a stem carried by the carriage to reciprocate vertically thereof, fluid pressure actuated means adapted to operate the stem, fluid pressure actuated means adapted to operate the slide relative to the table, an arm carried by the stem and projecting therefrom to approach the fixtures in said position when the carriage is in a predetermined position, and a jaw carried by the arm and adapted to clamp work at the fixtures when the carriage is in said position.

13. A machine for welding work parts including, an elongate horizontally disposed table, means supporting the table for longitudinal reciprocation, a slide on the table, means supporting the slide for reciprocation transversely of the table, rests mounted on the slide and adapted to be selectively moved by the slide into a predetermined position, a single retainer on the table, means mounting the retainer to move relative to the table into and out of work holding position at the rest in said position, a carriage on the table, means mounting the carriage to reciprocate longitudinally of the table, a stem shiftably carried by the carriage to reciprocate vertically relative thereto, an arm carried by the stem and projecting therefrom to approach the rest in said position when the carriage is in a predetermined position, and a jaw carried by the arm and adapted to clamp work at the last mentioned rest when the carriage is in said position.

14. A machine for welding work parts including, an elongate horizontally disposed table, means supporting the table for longitudinal reciprocation, fluid pressure actuated means adapted to operate the table, a slide on the table, means supporting the slide for reciprocation transversely of the table, rests mounted on the slide and adapted to be selectively moved by the slide into a predetermined position, a single retainer on the table, means mounting the retainer to move relative to the table into and out of work holding position at the rest in said position, fluid pressure actuated means adapted to operate the retainer, a carriage on the table, means mounting the carriage to reciprocate longitudinally of the table, fluid pressure actuated means adapted to operate the carriage, a stem shiftably carried by the carriage to reciprocate vertically relative thereto, fluid pressure actuated means adapted to operate the stem, fluid pressure actuated means adapted to operate the slide relative to the table, an arm carried by the stem and projecting therefrom to approach the rest in said position when the carriage is in a predetermined position, and a jaw carried by the arm and adapted to clamp work at the last mentioned rest when the carriage is in said position.

15. A machine for welding around rectangular work parts having vertically disposed peripheral walls projecting from a horizontally disposed base, including, a horizontally disposed table, means mounting the table for reciprocation, a fixture carried by the table and adapted to hold a work part, a carrier supported above the table, means mounting the carrier for reciprocation relative to the table, a spindle supported by the carrier to turn on a vertical axis relative thereto, welding means carried by the spindle and adapted to handle a welding rod and including, a head carried by the spindle and having a portion laterally spaced from the axis of the spindle, and an electrode carried by said portion of the head and projecting downwardly therefrom longitudinally of the spindle and toward the work part and angularly carrying a welding rod with the axis thereof intersecting the axis of the spindle and the terminal end thereof at the peripheral wall of the work part, and means whereby the table, the carrier and the spindle are operated relative to each other

in predetermined timed relation to move the work part relative to the welding means so straight predetermined welds are made at the periphery of the work part.

16. A machine for welding around rectangular work parts having vertically disposed peripheral walls projecting from a horizontally disposed base, including, a horizontally disposed table, means mounting the table for reciprocation, a fixture carried by the table and adapted to hold a work part, a carrier supported above the table, means mounting the carrier for reciprocation relative to the table, a spindle supported by the carrier to turn on a vertical axis relative thereto, welding means carried by the spindle and adapted to handle a welding rod and including, a head carried by the spindle and having a portion laterally spaced from the axis of the spindle, an electrode carried by said portion of the head and projecting downwardly therefrom longitudinally of the spindle and toward the work part and angularly carrying a welding rod with the axis thereof intersecting the axis of the spindle and the terminal end thereof at the peripheral wall of the work part, and a power driven rod feeding mechanism carried by the head and engageable with a rod handled by the electrode, and means whereby the table, the carrier and the spindle are operated relative to each other in predetermined timed relation to move the work part relative to the welding means so straight predetermined welds are made at the periphery of the work part.

17. A machine for welding work parts including, an elongate horizontally disposed table, means supporting the table for longitudinal reciprocation, a fixture mounted on the table and adapted to carry work parts, a carriage on the table, means mounting the carriage to reciprocate longitudinally of the table, a stem carried by the carriage to reciprocate vertically, an arm carried by the stem and projecting therefrom to approach the fixture when the carriage is in a predetermined position, a jaw carried by the arm and adapted to clamp work at the fixture when the carriage is in said position, a spindle supported above the table and mounted to rotate about an axis in a predetermined position relative to the fixture, and welding means carried by the spindle and adapted to handle a welding rod to effect welding of work at the fixture.

18. A machine for welding work parts including, an elongate horizontally disposed table, means supporting the table for longitudinal reciprocation, a fixture mounted on the table and adapted to carry work parts, a carriage on the table, means mounting the carriage to reciprocate longitudinally of the table, a stem carried by the carriage to reciprocate vertically, an arm carried by the stem and projecting therefrom to approach the fixture when the carriage is in a predetermined position, a jaw carried by the arm and adapted to clamp work at the fixture when the carriage is in said position, a spindle supported above the table and mounted to rotate about an axis in a predetermined position relative to the fixture, and welding means carried by the spindle and adapted to handle a welding rod to effect welding of work at the fixture and including, a head carried by the spindle and having a portion laterally spaced from the spindle, and an electrode carried by said portion of the head and projecting therefrom longitudinally of the spindle and toward the spindle and being adapted to carry a welding rod with a terminal end adjacent the axis of the spindle.

19. A machine for welding work parts including, a table, means mounting the table for reciprocation, a fixture carried by the table and adapted to hold work parts, a carrier supported above the table, means mounting the carrier for reciprocation relative to the table, a spindle supported by the carrier to turn relative thereto, means adapted to turn the spindle predetermined amounts at predetermined times during each cycle of operation

of the machine, welding means carried by the spindle and adapted to handle a welding rod, and means whereby the table, the carrier and the spindle are operated relative to each other in predetermined timed relation to move the work parts relative to the welding means so a predetermined weld is made on the work parts.

20. A machine for welding work parts including, a horizontally disposed table, means mounting the table for reciprocation, a fixture carried by the table and adapted to hold work parts, a carrier supported above the table, means mounting the carrier for reciprocation relative to the table in a direction transverse of the direction of movement of the table and in a position above the table, a vertically disposed spindle supported by the carrier to turn relative thereto, means adapted to turn the spindle predetermined amounts at predetermined times during each cycle of operation of the machine and including, circumferentially spaced pins on the spindle, and a pusher mounted to reciprocate and engageable with the pins, welding means carried by the spindle and adapted to handle a welding rod, and means whereby the table, the carrier and the spindle are operated relative to each other in predetermined timed relation to move the work parts relative to the welding means so a predetermined weld is made on the work parts.

21. A machine for welding work parts including, a horizontally disposed table, means mounting the table for reciprocation, a fixture carried by the table and adapted to hold work parts, a carrier supported above the table, means mounting the carrier for reciprocation relative to the table in a direction transverse of the direction of movement of the table and in a position above the table, a vertically disposed spindle supported by the carrier to turn relative thereto, means adapted to turn the spindle predetermined amounts at predetermined times during each cycle of operation of the machine and including, circumferentially spaced pins on the spindle, and a pusher mounted to reciprocate and engageable with the pins, welding means carried by the spindle and adapted to handle a welding rod, and means whereby the table, the carrier and the spindle are operated relative to each other in predetermined timed relation to move the work parts relative to the welding means so a predetermined weld is made on the work parts.

22. A machine for welding work parts including, a table, means mounting the table for reciprocation, a fixture carried by the table and adapted to hold work parts, a carrier supported above the table, means mounting the carrier for reciprocation relative to the table, a spindle supported by the carrier to turn relative thereto, means adapted to turn the spindle predetermined amounts at predetermined times during each cycle of operation of the machine, fluid pressure actuated means adapted to operate said last mentioned means, welding means carried by the spindle and adapted to handle a welding rod, and means whereby the table, the carrier and the spindle are operated relative to each other in predetermined timed relation to move the work parts relative to the welding means so a predetermined weld is made on the work parts.

23. A machine for welding work parts including, an elongate horizontally disposed table, means supporting the table for longitudinal reciprocation, a fixture mounted on the table and adapted to carry work parts, a carriage on the table, means mounting the carriage to reciprocate longitudinally of the table, a stem carried by the carriage to reciprocate vertically, an arm carried by the stem and projecting therefrom to approach the fixture when the carriage is in a predetermined position, a jaw carried by

the arm and adapted to clamp work at the fixture when the carriage is in said position, a carrier supported above the table, means mounting the carrier for reciprocation transversely of the table, and welding means including an electrode carried by a spindle and adapted to carry a welding rod to cooperate with work at the fixture.

24. A machine for welding work parts including, an elongate horizontally disposed table, means supporting the table for longitudinal reciprocation, a fixture mounted on the table and adapted to carry work parts, a carriage on the table, means mounting the carriage to reciprocate longitudinally of the table, a stem carried by the carriage to reciprocate vertically, an arm carried by the stem and projecting therefrom to approach the fixture when the carriage is in a predetermined position, a jaw carried by the arm and adapted to clamp work at the fixture when the carriage is in said position, a carrier supported above the table, means mounting the carrier for reciprocation transversely of the table, welding means including an electrode carried by a spindle and adapted to carry a welding rod to cooperate with work at the fixture, and means adapted to turn the spindle predetermined amounts at predetermined times during each cycle of operation of the machine.

25. A machine for welding around the peripheries of rectangular work parts including, a horizontally disposed table, means mounting the table for reciprocation, a fluid pressure actuated mechanism reciprocating the table, a fixture carried by the table and to position a work part, a carrier supported above the table, means mounting the carrier for reciprocation relative to the table, a fluid pressure actuated mechanism reciprocating the carrier, a vertically disposed spindle supported by the carrier to turn relative thereto, a fluid pressure actuated mechanism rotating the spindle, welding means carried by the spindle and angularly carrying a welding rod with the terminal end thereof adjacent the axis of the spindle, and means whereby the table, the carrier and the spindle are operated relative to each other in predetermined timed relation to move the work parts relative to the welding means so straight predetermined welds are made at the periphery of the work parts including, a hydraulic system with valves controlling said mechanisms, and an electrical control system operating the control valves in predetermined timed relation.

26. A machine for welding around the peripheries of rectangular work parts including, a horizontally disposed table, means mounting the table for reciprocation, a fluid pressure actuated mechanism reciprocating the table, a fixture carried by the table to position a work part, a carrier supported above the table, means mounting the carrier for reciprocation relative to the table, a fluid pressure actuated mechanism reciprocating the carrier, a vertically disposed spindle supported by the carrier to turn relative thereto, a fluid pressure actuated mechanism rotating the spindle, welding means carried by the spindle and angularly carrying a welding rod with the terminal end thereof adjacent the axis of the spindle, and means whereby the table, the carrier and the spindle are operated relative to each other in predetermined timed relation to move the work part relative to the welding means so straight predetermined welds are made at the periphery of the work parts including, a hydraulic system with valves controlling said mechanisms, and an electrical control system operating the control valves in predetermined timed relation and including electromagnetic operators operatively connected with the valves, and a circuit controlling the operators and including switches and timers cooperatively related to each other and to the table and the carrier.

27. A machine for welding around the peripheries of rectangular work parts including, a horizontally disposed table, means mounting the table for reciprocation, a fluid pressure actuated mechanism reciprocating the table, a fixture carried by the table to position a work part, a

carrier supported above the table, means mounting the carrier for reciprocation relative to the table, a fluid pressure actuated mechanism reciprocating the carrier, a vertically disposed spindle supported by the carrier to turn relative thereto, a fluid pressure actuated mechanism rotating the spindle, welding means carried by the spindle and angularly carrying a welding rod with the terminal end thereof adjacent the axis of the spindle, and means whereby the table, the carrier, and the spindle are operated relative to each other in predetermined timed relation to move the work part relative to the welding means so straight predetermined welds are made at the periphery of the work part and including, a hydraulic system with control valves controlling said mechanisms and stop valves controlling general flow of fluid in the system and being closed except when the machine is in operation, and an electrical control system operating the control valves in predetermined timed relation, and including electromagnetic operators operatively connected with the valves, and a circuit controlling the operators and including switches and timers cooperatively related to each other and to the table and the carrier.

28. A machine for welding around the peripheries of rectangular work parts including, a horizontally disposed table, means mounting the table for reciprocation, a slide mounted to reciprocate transversely of the table, a fluid pressure actuated mechanism reciprocating the slide, a fluid pressure actuated mechanism reciprocating the table, a fixture carried by the slide on the table to position a work part, a carrier supported above the table, means mounting the carrier for reciprocation relative to the table, a fluid pressure actuated mechanism reciprocating the carrier, a vertically disposed spindle supported by the carrier to turn relative thereto, a fluid pressure actuated mechanism rotating the spindle, welding means carried by the spindle and angularly carrying a welding rod with the terminal end thereof adjacent the axis of the spindle, and means whereby the table, the carrier, the slide and the spindle are operated relative to each other in predetermined timed relation to move the work part relative to the welding means so straight predetermined welds are made at the periphery of the work part and including, a hydraulic system with control valves controlling said mechanisms, and an electrical control system operating the control valves in predetermined timed relation and including, electromagnetic operators operatively connected with the valves, and a circuit controlling the operators and including, switches and timers cooperatively related to each other and to the table and the carrier, one switch being a main starter switch to be manually operated and two other switches being secondary starter switches in parallel with each other and with the main starter switch and related to the slide and controlling operating thereof.
